US00D901306S

(12) **United States Design Patent** (10) Patent No.: **US D901,306 S**
(45) Date of Patent: **** Nov. 10, 2020**

(54) **MEDIA BOTTLE**

(71) Applicant: **LIFE TECHNOLOGIES CORPORATION**, Carlsbad, CA (US)

(72) Inventors: **Paul Clark**, Youngstown, NY (US); **Sandro Klein**, Irvine, CA (US); **Xin Mathers**, Poway, CA (US); **Jeffrey Kelly**, Glasgow (GB); **David Judd**, Grand Island, NY (US); **Scott Glassman**, Clarence, NY (US); **Michael Scribner**, Sanborn, NY (US); **Adrian Bird**, Bicester (GB); **Imran Mahmood**, San Marcos, CA (US)

(73) Assignee: **LIFE TECHNOLOGIES CORPORATION**, Carlsbad, CA (US)

(**) Term: **15 Years**

(21) Appl. No.: **29/680,401**

(22) Filed: **Feb. 15, 2019**

Related U.S. Application Data

(60) Continuation of application No. 29/612,161, filed on Jul. 28, 2017, now Pat. No. Des. 840,826, which is a division of application No. 29/491,989, filed on May 27, 2014, now Pat. No. Des. 796,956.
